CLAIM

The ornamental design for a bird feeder hanger, as shown
and described.

DESCRIPTION

FIG. 1 is a perspective view of the bird feeder hanger
showing my new design;

FIG. 2 is a reduced top plan view thereof;

FIG. 3 is a front elevational view thereof;

FIG. 4 is an elevational view taken from the right side of
FIG. 3, the left elevational view being a mirror image
thereof;

FIG. 5 is a rear elevational view thereof;

FIG. 6 is a bottom plan view thereof; and,

FIG. 7 is an enlarged top plan view of the lower end of the
invention.
